CLAIM

The ornamental design for an electric gripper, as shown and described.

DESCRIPTION

FIG. 1 is a perspective view of an electric gripper showing our new design;

FIG. 2 is another perspective view thereof;

FIG. 3 is a front elevation view thereof;

FIG. 4 is rear elevation view thereof;

FIG. 5 is a left-side elevation view thereof;

FIG. 6 is a right-side elevation view thereof;

FIG. 7 is a top plan view thereof;

FIG. 8 is bottom plan view thereof;

FIG. 9 is an enlarged detail view defined by sections A-A and B-B in FIG. 1 thereof; and,

FIG. 10 is a cross-sectional view taken along line 10-10 in FIG. 3, with an internal mechanism omitted.

The broken lines depict portions of the electric gripper that form no part of the claimed design. The dot-dash boundary lines define the boundary of the claimed design and form no part of the claimed design. The particular cross-hatching patterns in the drawings are generic to all materials and are not limited to any particular material.
